PERMUTATION LOCK

George Rowland Lovelace Semple Fisher,
Pendock, Staunton, EnglandApplication May 31, 1945, Serial No. 596,880
In Great Britain June 6, 1944

7 Claims. (Cl. 70—312)

1

This invention relates to permutation locks of the type wherein one or more rings bearing indicia are rotatable about an axis coincident with the axis of a bolt so that when said rings are turned into a predetermined position the bolt may be displaced axially to effect unlocking.

One object is to provide a permutation lock suitable for a variety of uses such as the securing of a spare wheel to an automobile body, the locking of a manual control lever such as a vehicle hand brake, and the like.

Another object is the provision of a lock structure suitable for padlocks and the like.

A further object is to enable the unlocking permutation to be changed at will by the owner or authorised user of a permutation lock.

A still further object is to render the process of attempting to effect unlocking by feel or sound substantially impossible or highly wasteful of time.

According to the present invention, in a permutation lock of the type having a plurality of indicia bearing rings acting in conjunction with a plurality of members, in the form of balls to provide locking means for a bolt, a plunger is axially displaceable relative to the rings to move the balls clear of notches on the internal peripheries of the rings when the releasing permutation is selected so that said rings may be freely rotated to impart a new releasing permutation to the lock.

By providing a plunger displaceable axially to move the balls axially clear of notches on the internal peripheries of the indicia bearing rings and accommodating the balls in slots in a flange on said plunger or by providing a means for the bolt to be displaceable axially to cause radial disengagement of the balls from the notches and accommodating the balls in radial recesses, said rings may be displaced relative to the balls.

A dust cap is adapted to cooperate with an additional locking means whereby unlocking can only be effected when said indicia are covered.

By providing a spring loaded pin adapted to be engageable in a radial bore in the bolt, the additional locking means may be constituted due to pressure from the dust cap on to said spring loaded pin. The said dust cap may be cylindrical and moving in guides coaxially with the bolt.

The invention will be more particularly described, with reference to the accompanying drawing showing automobile spare wheel and brake locks, by way of example.

Figure 39 is a view partly in vertical section showing details of the said lock attached to another particular form of brake control.

Figure 40 is a view partly in elevation and partly in section of the assembly shown in Fig. 39.

The drawings show two forms of lock illustrative of my invention. Referring in the first instance to the one lock shown in Figs. 1, 2 and 3 it may be seen that this lock comprises a case generally designated 41 to which is secured a front guide 42 and an outer guide 43 thus forming a rigid casing to contain the lock mechanism. A slot 42a in the front guide and a slot 43a in the outer guide are in line when the casing is thus assembled. A dust cap 44 is disposed around the case 41 and moves in guides formed by lateral flanges 42b and 43b on the periphery of the front guide and outer guide respectively. This dust cap has ends 44a and 44b.

Within the casing of the lock are positioned a spacer ring 45, two indicia bearing rings 46 and 47 and a plunger 48 all coaxial with a bolt 49 which passes into the casing of the lock through an axial bore 42c in the front guide and an axial bore 45a in the spacer ring and which locates in a counterbore 43c in the outer guide. The spacer ring 45 is located intermediate the two indicia bearing rings 46 and 47. The bolt 49 is provided with an axial bore 49a and longitudinally recessed to present a radial slot 49b. The plunger 48 is positioned with plunger body 48a within the bore 49a of the bolt 49 and is held normally with a shoulder 48b against the end of the counterbore 43c in the outer guide by means of a spring 50 acting between the end of a counterbore 43d and the under surface of a domed cap 51 which is screwed to the end of a shank 48c on the plunger.

passing through an axial bore 43e in the outer guide. A radial flange 48d on the plunger passes through the radial slot 49b in the bolt 49 and engages in the slot 42a, the slot 43a and a slot 45b in the spacer ring 45, this spacer ring and the bolt 49 thereby being prevented from rotating. It will be seen that depression of the cap 51 against the spring 50 will cause an axial displacement of the plunger 48, the amount of displacement being governed by the length of the slot 42a in the front guide. This action is for a purpose later to be described.

The indicia bearing ring 46 has lateral flanges 46a and 46b and these engage over a lateral flange 42d on the front guide and a lateral flange 45c on the spacer ring thereby enabling the indicia bearing ring to rotate coaxially with the bolt 49. The internal periphery of the indicia bearing ring has sixteen notches 46c and a ball 52 lies in a peripheral groove 49c on the bolt 49 and within one of these notches, being constrained from movement parallel to the bolt axis by face 42e of the front guide and the face 45d of the spacer ring and occupying with a minimum of play the space between the groove in the bolt and the notch in the indicia bearing ring. It will be seen therefore that as the indicia bearing ring 46 is rotated the ball 52 will be carried around the groove in the bolt 49, a slot 48e allowing the ball to pass through the flange 48d on the plunger.

Another ball 53 is controlled in a like manner by the indicia bearing ring 47 rotating between the spacer ring 45 and the outer guide 43.

It will be seen that when the indicia bearing rings 46 and 47 are rotated so as to bring the balls 52 and 53 into alignment opposite the slot 49b in the bolt, the position as shown in Fig. 1, the bolt may be withdrawn axially from the lock. When either or both of the two balls are in any position other than opposite the slot in the bolt then it will be seen that the bolt may not be withdrawn from the lock.

A ratchet mechanism comprising a spring 54 and the balls 55 and 56 located in a slot 45e in the spacer ring 45, the two balls engaging in the radial grooves 46d and 47d of the indicia bearing rings 46 and 47, is included in the lock for the primary reason of holding the two indicia bearing rings in position when the bolt is withdrawn thus keeping the two balls 52 and 53 constrained within the two slots 48e and 48f of the plunger flange.

The ratchet, however, fulfills two further purposes. Should the lock be used under conditions wherein it is subject to vibration the indicia bearing rings will be prevented from rotating and thus possibly freeing the bolt. Further the clicks of the ratchet as the indicia bearing rings are rotated will tend to confuse any effort on the part of any person not aware of the correct releasing permutation of the lock to release the lock by rotating each indicia bearing ring in turn and listening for a possible click as each ball comes opposite the slot in the bolt.

For the purpose of fixing any required combination for the lock the indicia bearing rings 46 and 47 are provided with indicia on their external periphery so arranged that when any indicium is opposite a mark which may be provided on the external periphery of the spacer ring 45 a corresponding notch on the internal periphery of the indicia bearing ring 46 is opposite the slot 49b in the bolt. These indicia are visible through an aperture 41a in the case 41, which aperture also gives access for manipulating the

indicia bearing rings, manipulation being assisted by the grooves 46e parallel to the axis on the external periphery of the indicia bearing rings.

An additional locking device is incorporated in this lock as a further precaution against the lock being tampered with and opened by any person not fully conversant with the mechanism and this device operates in conjunction with the dust cover 41. In order to manipulate the indicia bearing rings the dust cover must be rotated so that the gap between the ends 44a and 44b is located over the aperture 41a in the case. When in this position a locking pin 57 operating in a radial bore 45f and a counterbore 45g of the spacer ring is depressed against a light spring 58 by the dust cap bearing on a shank 57a which is located in a radial bore 41b in the case 41. When thus depressed the tip of the locking pin engages a radial bore 49d in the bolt. It will thus be seen that even if the indicia bearing rings are manipulated to the correct releasing permutation the bolt may not be withdrawn until the dust cap has been closed, i. e. until either of the ends 44a or 44b has passed clear of the shank of the locking pin thus allowing the spring 58 to return the locking pin to its normal position with the tip withdrawn inside the bore 45f of the spacer ring. When the dust cap is again rotated in order to operate the lock the locking pin 57 is automatically depressed as one of the ends 44a or 44b of the dust cap passes over the shank 57a.

In order to alter the releasing permutation of the lock slots 42f and 45h are provided in the front guide and spacer ring respectively.

By depressing the cap 51 against the spring 50 as previously described the plunger 48 will be displaced axially, and if the lock is set at its releasing permutation the balls 52 and 53, which will be located in the slots 46e and 48f of the plunger, will be carried into the slots 42f and 45h. With the cap 51 held depressed the indicia bearing rings 46 and 47 may then be rotated to any desired setting, and on releasing the cap the plunger 48 will be returned to its normal position by the spring 50 and the balls 52 and 53 will be repositioned in different notches in the two indicia bearing rings according to the releasing permutation chosen.

In Fig. 1 the lock is shown in this specific instance as securing the spare wheel of an automobile by the bolt passing through a hole in a bracket 59, which may be attached to the automobile body, and a hole 60 which may be in the wheel disc.

Referring now especially to Figs. 21, 22, 23, 37 and 38 the second lock may be seen to comprise a case generally designated 61 in which are positioned two indicia bearing rings 62 and 63, a spacer ring 64 intermediate the two indicia bearing rings, an end guide 65 which is secured to the case. It will be seen that the two indicia-bearing rings may rotate coaxially in a manner similar to that previously described for the lock shown in Fig. 1 against a ratchet comprising a spring 66 and two balls 67 and 68 located in an axial slot 64a in the spacer ring. The indicia bearing rings have grooves parallel to the axis on their external periphery and are visible through an aperture 61a in the case. In this lock the spacer ring is provided with a flat 64b which affords easier manipulation of the indicia bearing rings.

A plunger bolt 69 operates in the coaxial bores 61b, 64c and counter bore 65a of the case, spacer

ring and end guide respectively; two peripheral grooves 69a and 69b accommodating two balls 70 and 71, located in notches on the internal periphery of the indicia bearing rings 62 and 63.

5 The plunger bolt is longitudinally recessed to present a groove 69c thereby permitting the plunger bolt to be displaced axially when the two balls are brought into alignment opposite the groove. This groove also engages with a lug 61c in the bore 61b of the case 61 and a lug 64d in the bore 64c of the spacer ring 64 and thus prevents rotation of the plunger bolt and the spacer ring within the case.

10 The diametrical bore 61d of the case engages over a lever 72 of a hand brake control and the plunger bolt 69 locates in an aperture 72a. When the lock is closed the tip 69d of the plunger bolt engages a recess 73a in a lever 73 which operates the brake ratchet and so prevents the lever from being depressed in order to free the brake.

15 If the indicia bearing rings of the lock are rotated to the releasing permutation the plunger bolt is free to move axially against a spring 74 and thus allow the rod 73 to be depressed and the brake released. The spring 74 ensures that the tip of the plunger bolt re-engages with the recess in the brake lever when the brake control has been set at any desired position and the brake ratchet released.

20 To provide means for altering the releasing permutation of the lock radial recesses 69e and 69f are provided in the axial groove 69c of the plunger bolt. When the lock is set at its releasing permutation and the ratchet rod 73 is depressed the plunger bolt will, as previously described, be displaced axially against spring 74. The radial flange 69g at the head of the shank 69h of the plunger bolt will now protrude outside the casing of the lock through the axial bore 45b in the end guide 65. If the shank is now withdrawn still further by hand the balls 70 and 71 will fall into the recesses 69e and 69f and the indicia bearing rings may be rotated to any desired releasing permutation. On releasing the plunger bolt the balls will be forced back into normal position in notches in the indicia bearing rings.

25 Figs. 39 and 40 indicate the type of lock just described used in conjunction with another type of handbrake control.

30 In this application the lock case 61 is swingably connected to a lever 75 by means of a lug 61e. An extension 69i of the plunger bolt 69 is swingably connected to a control lever 76 which 35 operates the brake ratchet through a rod 77. When the lock is closed the plunger bolt 69 and hence the extension 69i is fixed so prevents axial displacement thereof, which in turn prevents the brake from being released.

35 The releasing permutation may be altered by setting the lock at its releasing combination and axially displacing the plunger bolt against the spring 74 by means of the lever 76 until the balls 70 and 71 fall into the recesses 69e and 69f then 40 the indicia bearing rings may be rotated to any desired permutation. On releasing the lever 76 the plunger bolt will return to its normal position under the influence of the spring 74, and hence the balls will be forced back into normal 45 position in notches in the indicia bearing rings. The recesses 69e and 69f may be placed in a position so that under normal operation of the brake the plunger bolt will not be axially moved to the extent required for altering the permutation.

scribed thus includes a hollow body or case 41 or 61 and at least two indicia bearing rings 46 and 47 or 62 and 63 respectively, rotatably mounted in spaced relationship on the body and notched, for example, at 46c and 47c; a bolt 49 or 69 adapted to be received within the body, the bolt being peripherally grooved at 49c or 69a and 69b, one groove to each ring and longitudinally recessed at 49b or 69c, the recess intersecting the respective peripheral grooves; means to support the balls when aligned with the recess independently of the bolt, the dimensions being such that the bolt can only be withdrawn when the rings have been rotated to a position wherein their indicia present the selected releasing permutation due to at least one of the balls of the pairs 52 and 53 or 70 and 71 engaging against its corresponding groove in other positions of the ring. The improvement whereby reselection of the releasing permutation may be effected consists in means to accommodate the two balls each in a position clear of its corresponding ring except when the two balls have been simultaneously aligned to permit release of the bolt.

It is to be understood that the above described embodiments of my invention are for the purpose of illustration only and various changes may be made therein without departing from the spirit and scope of the invention.

I declare that what I claim is:

1. A permutation lock of the type referred to comprising a hollow body; a number of rings bearing indicia and having their inner periphery notched, rotatable with respect to said body; a bolt peripherally grooved, one groove to each ring, and axially grooved, the axial groove running into each peripheral groove; a number of balls, one ball to each ring; spacing means between adjacent indicia bearing rings; a number of means intermediate the rings and the bolt adapted each to constrain a single ball the diameter of which substantially occupies the full space between the bottom of a groove in the bolt and the bottom of one of the notches in the rings; a dust cap mounted for rotation about said body and having an opening through which part of said rings may be exposed; and means displaceable by said dust cap to effect additional locking when said rings are exposed.

2. A permutation lock of the type referred to comprising a hollow body; a number of rings bearing indicia and having their inner periphery notched, rotatable with respect to said body; a bolt axially bored and peripherally grooved, one groove to each ring; and axially slotted, the axial slot intersecting each peripheral groove and the axial bore; a number of balls, one ball to each ring; spacing means between adjacent indicia bearing rings; and an inner bolt slidable in the axial bore and having a radially and axially extending flange extending through said slot said flange being recessed to constrain a single ball the diameter of which substantially occupies the full space between the bolt and each ring in the unlocked position.

3. A permutation lock of the type referred to comprising a hollow body; a number of rings bearing indicia and having their inner periphery notched, rotatable with respect to said body; a

bolt peripherally grooved, one groove to each ring, and axially grooved, an axial groove running into each peripheral groove; a number of balls, one ball to each ring; a number of means intermediate the rings and the bolt adapted each to constrain a single ball the diameter of which substantially occupies the full space between the bottom of a groove in the bolt and the bottom of one of the notches in the rings; and means to displace said ball constraining means axially of the bolt; spring means adapted to resist such displacement; and means to accommodate each ball in an offset position relative to said rings to permit of reselection of a releasing permutation.

4. In a permutation lock of the kind which comprises a hollow body; a plurality of rings each bearing indicia and having a notched inner periphery, said rings being rotatably mounted in spaced relationship on said body; a number of balls, one ball to each ring; a bolt adapted to be received within said body, said bolt being peripherally grooved, one groove to each ring, and longitudinally recessed, the recess intersecting said grooves; means to support the balls when aligned with said recess independently of the bolt, the dimensions being such that the bolt can only be withdrawn when the rings have been rotated to a position wherein their indicia present the selected releasing permutation due to at least one of the balls engaging against its corresponding groove in other positions of the rings; the improvement whereby reselection of the releasing permutation may be effected consisting in means to accommodate all the balls each in a position clear of its corresponding ring when said balls have been simultaneously aligned to permit release of the bolt.

5. A permutation lock as set forth in claim 4 in which said last mentioned means is to accommodate each ball in an axially off set position relative to said rings to permit of reselection of a releasing permutation.

6. A permutation lock as set forth in claim 4 in which said last mentioned means is to accommodate each ball in a radially off set position relative to said rings to permit of reselection of a releasing permutation.

7. A permutation lock as set forth in claim 4 additionally comprising a dust cap mounted for rotation about said body and having an opening through which part of said rings may be exposed; and means displaceable by said dust cap to effect additional locking when said rings are exposed.

55 GEORGE ROWELAND LOVELACE
SIMPLE FISHER.
